UNITED STATES PATENT OFFICE.

CHARLES A. RASTETTER, OF FORT WAYNE, INDIANA.

MAIL RECEPTACLE.

Application filed February 2, 1924. Serial No. 690,161.

To all whom it may concern:

Be it known that I, CHARLES A. RASTETTER, a citizen of the United States of America, and resident of Fort Wayne, in the county of Allen and State of Indiana, have invented certain new and useful Improvements in Mail Receptacles, of which the following is a specification.

This invention relates to improvements in mail receptacles of that type adapted to be installed in the wall of a house and which will be accessible for reception of mail matter from the exterior of the building, and from which the mail matter deposited in the receptacle is removable from the interior of the house.

The object of the improvement is to provide a receptacle of its class so constructed that mail matter upon its reception will become visible from the interior of the house and which will admit of the overflow for an excess quantity of mail matter and thus obviate choking of the receptacle. Another object is to provide both visible and audible means of indicating the delivery of mail matter into the receptacle.

These objects are accomplished by the construction illustrated in the accompanying drawings in which:

Fig. 1 is a vertical section of a wall in which a mail receptacle embodying the invention is installed; and

Fig. 2 is a fragmentary rear elevation showing the method of securing the telescoping box sections together.

The characters appearing in the description refer to parts shown in the drawings and designated thereon by corresponding characters.

The invention comprises a receptacle formed of two box sections 1 and 2, the latter having a flange 3 that telescopes within the section 1 and closes the rear thereof. The flanges of the section 2 are secured fixedly to the corresponding sides 4 of the section 1 by means of screws 5 that extend through said flanges and corresponding slots 6 in the sides 4. Each screw has threaded connection with a binding block 7 so that when the screw is tightened in its block, the side 4 becomes clamped between the block and the flange 3. The section 1 is positioned in the wall 8 of the house and is secured therein by screws 9 that extend into the outer sheeting 10 of the wall, and the margin 11 surrounding the section 2 extends be-

yond the flange 3 and overlaps the plastering 12 adjacent the rear end of the section 1.

The receptacle has in its upper portion a receiving chute 13 that extends through the sheeting and the weather boarding 14 of the wall, the outer end of the chute being provided with a hinged cover 15 by which it is normally closed. The section 2 has a door 16 that swings upon a horizontal axis, there being a pin 17 at each side of the section 2 that extends through the corresponding side flange 18 of the door.

A stop 19 fixed within the section 1 is positioned so as to engage the inner end of the door when it reaches its horizontal position, the stop having a strip 20 of felt against which the door impinges and which deadens the shock of its contact with the stop. The door also has at the lower end of each of its side flanges a counter-weight 21 that tends to retain the door in closed position. But, the counterweights are of insufficient size as to overbalance the opposite end of the door when the door is in horizontal position, and therefore the door, when open, tends to remain in horizontal position. The pivots 17 are so located relative to the center of gravity of the weighted door that the preponderence of the weight, as the door swings from closed position to open position, and vice versa, passes over the axis upon which the door swings, and thus the door is held open or closed by its own inertia.

A lever 22 is loosely mounted on a stud 23 that projects from one side 4 of the receptacle and has a link connection 24 with a bracket 25 that projects from the inner face of the cover 15 into the chute so that when the cover is swung open the lever 22 is turned upon the stud with its lower end impinging against the adjacent side 18 of the door causing the door to open.

A pair of insulated electrical contact points 26 are positioned within the receptacle and have connection respectively with conductors 27 which are connected in circuit with an electric bell and source of energy therefor (not shown). The contact points are so located with respect to the upper end of the lever 22 that the electrical circuit becomes closed by the contact of the lever with said points during its inward and outward movements.

Also in the upper part of the receptacle is

a mechanical lever-actuated bell 28 and a rod 29 having pivotal connection with the lever 22 and the bell-actuating lever 30, the latter lever being operable through the 5 medium of the rod by the lever 22.

In the operation of the invention, mail matter is delivered by swinging the cover open and inserting the mail matter through the chute into the receptacle. The raising of 10 the cover causes the lever 22 to open the door so that it assumes horizontal position and exposes the interior of the receptacle. The mail matter passing through the chute lodges upon the horizontally positioned 15 door in clear view of the occupant of the house. Also as the cover is manipulated the circuit of the electrical bell is closed causing the bell, which may be remotely located, to be sounded as well as the mechanical bell 20 which is also actuated through movements of the cover. In this manner the deposit of mail matter into the receptacle is announced by the bells and visibly indicated by its lodgment upon the open door. When 25 the door is horizontal the receptacle is open so that in the event of a large quantity of mail-matter is delivered at one time, or by repeated deliveries, the overplus will pass from the chute through the receptacle and

over the door into the room of the building 30 without becoming jammed in the receptacle which would interfere with a further introduction of mail matter.

What I claim is:—

In a device of the class described, a receptacle composed of two telescoping sections; a door in one of said sections pivoted to swing upon a horizontal axis located below its centre of gravity and tending to remain open or closed by its inertia; a chute having 35 communication with the receptacle through the upper part of the other section, including a hinged cover for same; a pivoted lever having actuated relation with the cover and operable to swing the door open; a stop to 40 limit the opening movement of the door when it reaches horizontal position; and an- 45 nunciating means in connection with an operable by the lever, said door, when open, serving as a shelf for lodgment of the mail 50 matter introduced through the chute.

In testimony whereof I affix my signature in presence of two witnesses.
